UNITED STATES PATENT OFFICE.

JOHN MAWSON, OF VINE PLACE, SUNDERLAND, ENGLAND, ASSIGNOR, BY MESNE ASSIGNMENTS, TO CHAS. T. KNAFF, OF CHICAGO, ILLINOIS.

GAS PRODUCER.

Application filed October 7, 1920, Serial No. 415,249. Renewed June 27, 1927.

This invention relates to a process of and apparatus for producing combustible gases by the reaction of a heated fuel with air and water, and my object is to devise a process 5 of gas production and producer for use therein which will enable gas to be produced economically and with the use of a minimum amount of air.

I attain my object by means of the process 10 hereinafter set forth and by means of the constructions hereinafter described and illustrated in the accompanying drawings in which—

Fig. 1 is a vertical section of my improved 15 gas producer;

Fig. 2 is a cross section of half of the same on the line *a*—*b* in Fig. 1;

Fig. 3 is a vertical cross section of half 20 of the lower part of the generator taken on a plane at right angles to the plane of section of Fig. 1; and

Fig. 4 is a view similar to Fig. 2, showing a modification thereof.

In the drawings like numerals of reference 25 indicate corresponding parts in the different figures.

1 is the outer casing of the gas producer, which is preferably formed of sheet metal suitably heat insulated. A preferable plan 30 is to form the casing with double walls packed with asbestos or mineral wool. At the lower end of this casing is located the ashpit 2 of similar construction to the casing. The ashpit is provided with the usual 35 air-tight ashpit door 3. Spaced from the outer casing is an inner casing 4 the space between the two casings forming a vaporizing chamber 5.

Within the lower part of the inner casing 40 4 is located the firepot 6, the walls of which will usually be formed of some suitable refractory material and will be of considerable thickness, as shown.

7 is a feed tube for the fuel suitably supported from the casing, which feed tube is 45 of substantially the same cross sectional form and dimensions as the interior of the fire pot and extends down towards, but not quite to the upper end of the fire pot, thus forming with the upper part of the inner casing 50 a gas chamber 24. With the feed tube communicates the fuel hopper 8, preferably provided with two charging doors 9.

In the vaporizing chamber 5 is located the 55 vaporizing coil 10, which is of helical form

and located close to the outer wall of the inner casing 4, in which position it is best exposed to the conducted and radiated heat from the fire pot and gas space. At its upper end this coil extends out through the 60 outer casing and is connected with a suitable source of water supply, such, for example, as a tank 11. A suitable valve 12 is provided whereby the water supply may be controlled. The vaporizing coil has small 65 apertures *c* formed therein at different parts of its length through which water and vapor may escape to the vaporizing chamber. Any equivalent of the coil may of course be employed.

Special means are provided for introducing 70 an extra quantity of water into the vaporizing chamber at suitable times. These means comprise a single pipe or coil 20, preferably located at the top of the vaporizing chamber, and communicating with a separate tank 21 or other source of supply under pressure. This coil is preferably provided with small apertures *c'* through which the water may drip. A controlling valve 22 75 and drip tube 23 will also be provided by means of which the water admitted may be controlled and its flow observed.

With the vaporizing chamber communicates the pipe 14 through which air may be 80 blown, the gas chamber communicates with the gas outlet pipe 15. The fire pot is provided with any suitable form of gate. I prefer, however, to employ a grate *d* having a drop in the centre to allow of greater area 85 of air space in the grate than would otherwise be possible. It will be understood, of course, that in practice any suitable means may be provided for shaking the grate and for breaking up and extracting clinkers. 90

The lower end of the vaporizing chamber 5 is closed by an annular plate 17, save for an opening 18 at a point remote from the ashpit door. The grate is shielded by a hood 19, which is closed except at the front 100 adjacent to the ashpit door. The water vapor in the vaporizing chamber together with any air introduced through the pipe 14 thus travels to the back of the producer and all around the hood enclosing the grate before it can pass into the hood and then up through the grate into the fire bed of the producer. The steam and air introduced into the producer must therefore pass over a maximum of heating surface, so that they 105 110

acquire the temperature which I find is necessary to secure the reaction desired. The hood is, of course, sufficiently spaced from the grate to enable ashes to be readily raked out therefrom.

A very important feature of my invention is the shaping of the fire pot. As will be seen particularly on reference to Fig. 2, the fire pot in horizontal cross section is materially greater in diameter in one direction than in a direction substantially at right angles thereto, the preferred form being that of an oblong parallelogram with rounded corners as shown. Great surface area in proportion to cubical contents is thus obtained not only for the fire pot, but for the vaporizing chamber as well, which is of great advantage in the adequate heating of the steam and air admitted.

If greater capacity be desired in the vaporizing chamber its walls need not parallel the wall of the fire pot but might be made circular, see Fig. 4.

The mode of operation of the producer is substantially as follows. A lighted newspaper is inserted through the top and a suitable quantity of charcoal is immediately put in on top of the lighted paper. Air is then blown in through the air pipe 14, and as soon as the charcoal is well alight, the charcoal, coke, or other fuel, on which the producer operates is introduced. The fuel openings are closed and care is taken to see that they are properly sealed. Water is turned on as soon as the producer is closed and is allowed to drip slowly into the vaporizing coils 10 and 20. The blower is kept in operation until gas of suitable quality is being generated, when the air is closed off and a run is made introducing water only. At any time air may be blown in through the pipe 14 as may be necessary.

I find it desirable to maintain sufficient depth of fuel in the active fire zone to give thorough contact of the reactive gases and solids at the rate of flow of gas through the fuel bed which I find desirable, that is about one cubic foot per second. Length of contact between the reactive gases and solids at high temperatures is of the greatest importance in securing a gas of high thermal value rich in methane. The gas produced by my process I find on analysis to be a mixture of H_2 , CO , CH_4 , and C_2H_4 , in various proportions with a very little CO_2 , O_2 , and N_2 .

In operation the fuel bed after being fired is in constant activity without any lessening of such activity. The water is delivered in measured quantities into the vaporizer. It is there vaporized and delivered from the vaporizer and passes through the fire in measured quantities. This passing through the fuel zone is continuous and hence there can be and is no lessening of the activity of the firebed.

The present well known process designated "shooting the bed" is accomplished by projecting live steam into the heat zone. This gradually lowers the temperature and a stoppage must be made in the process until the heat is again raised. This is known as the intermittent process and is in general use in this country. It will readily be seen that my process is quite different. There is no stoppage of the process or of the delivery of the water into the vaporizer, for the water being in measured quantities delivers continuously and, as small amounts of air are added from time to time to supplement the oxygen of the disassociated steam when necessary, there is no lessening of the activity in the fire zone or lowering of the temperature therein.

To maintain the rate of flow the gas produced must pass away quickly and the vaporizing chamber must be supplied with water at a corresponding rate and the vaporized water must flow at the proper rate to the fuel bed. All this can best be accomplished by maintaining a suitable suction on the producer by any suitable means.

A very important feature of my process is that in the vaporizing chamber the water introduced is not only vaporized but is heated to a very high temperature so that the water enters the fuel in the form of a highly heated steam vapor which requires to take up very little extra heat to bring it to the temperature of reaction with the carbon and the fuel.

The result is that the process is very economical and that a gas of high thermal value is obtained containing a large proportion of methane and very little carbon dioxide and nitrogen.

What I claim as my invention is:—

1. A gas producer comprising outer and inner walls spaced apart forming a vaporizing chamber therebetween, a vaporizing coil in said chamber, a firepot shaped substantially as an oblong parallelogram, and surrounded by said vaporizing chamber, a grate having a sunken central portion at the bottom of the firepot, a hood beneath said grate spaced apart therefrom and having open communication at one end with said vaporizing chamber.

2. A gas producer provided with a fire pot having a grate at its bottom; a vaporizing chamber around the firepot; a closed ash pit below the grate communicating with the vaporizing chamber; and a hood fitted under the grate having an opening into the ash pit at one side of the grate.

3. A gas producer provided with a firepot having a grate at its bottom; a vaporizing chamber around the fire pot; a closed ash pit below the grate communicating with the vaporizing chamber at one side only of the grate; and a hood fitted under the grate

1. having an opening into the ashpit at the side of the grate opposite to the communication between the vaporizing chamber and the ashpit.
5. 4. A gas producer provided with a firepot having a large surface area in proportion to cubical contents, an outer casing spaced from the fire pot to form a vaporizing chamber, water vaporizing means located therein, an ashpit beneath the firepot and having communication with the vaporizing chamber, a hood beneath the fire pot but spaced apart therefrom and having open communication on one end thereof with the 10 ashpit, the steam discharging from the vaporizing chamber into the ashpit at the rear thereof, and passing through the open end of the hood to the firepot.
15. 5. A gas producer provided with a firepot having a grate at its bottom; a vaporizing chamber about the firepot; a closed ashpit below the grate; an annular plate closing the bottom of the vaporizing chamber and having an opening at one side communicating with the vaporizing chamber; and a hood fitted under the grate having an opening into the ashpit at one side of the grate.
20. 6. A gas producer having a firepot which in horizontal cross section is greater in diameter in one direction than in a direction substantially at right angles to the direction of greatest diameter; a grate at the bottom of the firepot; a vaporizing chamber about the firepot; a closed ashpit below the grate communicating with the vaporizing chamber at one end of the greatest diameter of the firepot; a hood fitted under the grate opening into the ashpit at the side substantially diametrically opposite the communication 25 between the ashpit and the vaporizing chamber.
25. 7. A gas producer comprising outer and inner walls spaced apart and forming a vaporizing chamber therebetween; a firepot within the inner walls, a grate for the firepot, a gas chamber within the inner walls above the firepot, an ashpit below the grate, a feed tube discharging towards the firepot, a gas outlet extending from the aforesaid gas chamber, a vaporizing coil in the vaporizing chamber, said coil having apertures therein at intervals along the entire length thereof, and means for introducing water in said vaporizing chamber independent of the aforesaid vaporizing coil.
30. 8. In a gas producer, the combination of outer and inner walls spaced apart to form a vaporizing chamber therebetween, a firepot within the inner wall which in horizontal section is greater in diameter in one direction than in a direction at right angles thereto, a vaporizing coil extending from the top to the bottom of the vaporizing chamber in a helical direction, and means for introducing air and water into the vaporizing chamber and water into the coil independently of each other, and directing the flow of gases from the vaporizing chamber into the firepot of the producer.
35. 9. In a gas producer, the combination of outer and inner walls spaced apart to form a vaporizing chamber therebetween of approximately circular cross section, a firepot within the inner walls which is greater in diameter in one direction than in a direction at right angles thereto, a grate for said firepot, a gas chamber above the firepot, an ashpit below the grate, a helical vaporizing coil in the aforesaid vaporizing chamber, extending from the top to the bottom thereof, and having a plurality of openings formed along the length thereof, means for supplying water to said vaporizing coil, and means for supplying water and air to the vaporizing chamber independently of the aforesaid coil.
40. 10. In a gas producer, the combination of outer and inner walls spaced apart to form a vaporizing chamber therebetween, a firepot within the inner wall which in horizontal section is greater in diameter in one direction than in a direction at right angles thereto, a vaporizing coil extending from the top to the bottom of the vaporizing chamber in a helical direction, and means for introducing air and water into the vaporizing chamber and water into the coil independently of each other, and directing the flow of gases from the vaporizing chamber into the firepot of the producer.
45. 11. A gas producer including in combination concentric walls spaced apart from each other forming a vaporizing chamber extending from the top to the bottom of said walls, a perforated coil between said walls forming a helically shaped vaporizer in which steam is generated and directed into the aforesaid vaporizing chamber, a firepot within the inner wall which is larger in diameter in one direction than in the other, a grate for said firepot, a gas chamber above the grate formed partly by said inner wall, an ashpit below the grate, and a hood beneath said grate, said hood having an opening at one end thereof, through which the steam from the vaporizing chamber travels on its way to the firepot of the producer.
50. 12. A gas producer including in combination concentric walls spaced apart from each other forming a vaporizing chamber, a firepot inside the inner wall, a grate, a gas chamber above the firepot, an ashpit below said grate, a hood beneath said grate having an opening in one end thereof, a perforated coil between said walls forming a helical vaporizer extending from the top to the 55 inner wall of the gas chamber above the

bottom of the inner wall in which steam may be generated and introduced into said vaporizing chamber and the resultant steam led into the ashpit, through the hood into 5 the firepot of the producer.

13. A gas producer including in combination concentric walls spaced apart from each other forming a vaporizing chamber having a discharge opening at one side of its bottom; 10 a perforated coil in said chamber, a source of water supply for said coil, an inlet pipe for water opening into the upper

part of said coil, a firepot within the inner wall, a grate for the firepot, a gas chamber above the firepot, and a hood beneath 15 said grate having an opening in one side farthest from the discharge opening from the vaporizing chamber whereby steam from the vaporizing chamber may pass to the firepot of the producer.

Signed at Chicago, Ill., this 28th day of September, 1920.

JOHN MAWSON.
